UNITED STATES PATENT OFFICE.

SAMUEL C. SWISHER, OF SAN BERNARDINO, CALIFORNIA, ASSIGNOR TO ROSS W. MARKEL, OF SAN BERNARDINO, CALIFORNIA.

ROPE-CLAMP.

1,159,616.

Specification of Letters Patent.

Patented Nov. 9, 1915.

Application filed October 31, 1914. Serial No. 869,596.

To all whom it may concern:

Be it known that I, SAMUEL C. SWISHER, a citizen of the United States of America, residing at San Bernardino, in the county of San Bernardino and State of California, have invented certain new and useful Improvements in Rope-Clamps, of which the following is a specification.

The present invention relates to improvements in rope clamps, and while it is designed especially for pulling large wires and cables as used by electric light, street car and other electrical construction, and also for pulling ropes used by riggers, it will of course be understood that the rope clamp is applicable for use wherever such an implement is required. In pulling ropes, cables, and wires, a clamp is required which may be quickly applied, and with equal quickness and facility be detached from the rope, and which, when in use, shall be clamped to hold the rope securely and without slipping.

By the utilization of my device the rope may be clamped at any desired point for pulling, and the device may be shifted along the rope or cable with facility and adjusted to the proper point at which the pull is to be applied.

30. The invention consists essentially in certain novel combinations and arrangements of clamping means used in connection with a pair of clamping blocks, as will be more fully hereinafter described and claimed.

35. In the accompanying drawings I have illustrated one complete example of the physical embodiment of my invention, and a modified form of one of the clamp blocks, constructed according to the best modes I have so far devised for the practical application of the principles of the invention.

Figure 1 is a side elevation of the clamping device operatively applied to a rope or cable. Fig. 2 is a plan view of the device laid open. Fig. 3 is a transverse sectional view on line 3—3, Fig. 1. Fig. 4 is a central longitudinal vertical section of one of the clamp blocks showing the friction groove for the rope. Fig. 5 is a plan view of one of the cleats with an eye at the end, and Fig. 6 is a side view of the same cleat. Fig. 7 is a plan view of a cleat with a hook, and Fig. 8 is a side view of the same cleat. Fig. 9 is a view of a double cleat, one of which is used at one end of each clamp block. Fig. 10 is a

side elevation of a portion of two blocks, showing not only the friction groove curved, but showing the faces of the blocks curved as well.

In the preferred embodiment of my invention as illustrated in the drawings, I employ two clamping blocks as 1 and 2, which may be made of suitable material either wood or metal, and in some instances the wooden blocks are lined or faced with metal plates. These blocks are of suitable dimensions, and they may be varied in size to adapt them to different sized ropes, cables or wires. One face of each block, the faces which are opposite each other when the blocks are in operative position, is grooved from end to end, as shown in Fig. 2, where the groove in the block 1 is indicated as 3, and the groove in the block 2 is indicated as 4. The grooves are of suitable size to accommodate several sizes of cable or rope, and in Figs. 1 and 4, it will be seen that the grooves follow a compound curve from one end of the block to the other. This formation of groove is provided in order that the cable or wire may be rigidly held between the two blocks, because of the increased friction and grip with which the blocks are clamped to the cable or wire.

Each of the blocks is equipped with a series of metallic cleats or straps spaced apart at convenient intervals throughout the length of the block, and these cleats not only strengthen the wooden blocks themselves, but serve the purpose of supporting the means for clamping the blocks on the wire or cable 5. There are two forms of these metallic cleats or straps, as best shown in Figs. 5 to 8, Figs. 5 and 6 illustrating a cleat 6 with an eye 7 turned up at one end, and Figs. 7 and 8 illustrating a cleat 8 with a hook 9 forming one terminal of the strap. One end of all of the cleats is turned over to form a hook as 10, which hook engages over an edge or corner of the blocks to which it is attached by screws or bolts passed through the openings 11 in the cleat. It will be readily seen that these cleats are located transversely of the blocks, so that the hooks 9 and eyes 7 are positioned at opposite sides of the block.

In Fig. 2 it will be seen that there are four eyes 7 in juxtaposition, when the clamp is turned open, and through these eyes the end portion 12 of the flexible wire or pull

rope is passed, and this arrangement of rope and eyes forms a hinge for the two blocks.

In Fig. 1, it will be seen that the other end 13 of the pull rope is passed through two eyes on the upper block 1, and looped around two hooks on the lower block. This arrangement provides for the easy attachment and detachment of the clamp to the rope.

The extreme ends of the pull rope are 10 provided with eyes 14 and 15, and each of these eyes is adapted to engage a loop 16 formed at the bend between a double cleat which is fashioned with a pair of straps 17 and 18. In Fig. 9, as well as in Fig. 1, it 15 will readily be seen that these two straps 17 and 18 are arranged in planes at right angles to each other, and each is provided with an end hook 19 adapted to engage over the corner or edge of a block in manner 20 similar to that of the hook 10 on the other cleats. This double cleat is secured to the block by screws or bolts passed through perforations 20 in each strap of the cleat, and in Figs. 1 and 2, it will readily be seen that 25 the cleat with its double straps is attached to the end of a block and also to the bottom or top of the block, as the case may be. The bends 16 are spaced away from the block a suitable distance to form a loop for the eyes 30 14 or 15, so that said eyes will loosely engage these loops. The pull rope is provided with a flexible shield 21 to which the pulling device is applied when it is desired to use the rope clamp for the purpose of pulling 35 a rope or cable.

In Fig. 10, the blocks 1^a, 2^a have a groove 3^a extending through the face of each, but in this instance the groove is of equal depth throughout the length of the block. However, the face 4^a of the block is curved or undulating, and by this means the same effect is attained as when the grooves are of varying depths as in Figs. 1 and 2.

In using the rope clamp, it is opened back, 45 as shown in Fig. 2, with the pull rope passing through the adjoining eyes of the complementary blocks and forming a hinge. This arrangement of rope and eyes insures against loss of the blocks or displacement of 50 the same, and forms a convenient means of opening or detaching the clamp from the wire or cable. When the clamp is to be applied, the wire or cable is laid in the groove 4, then the block 1 is folded over on top of 55 the wire or cable with the groove 3 fitting

in close frictional contact. The end 13 of the wire is then passed under the two hooks 9 on the block 2. The clamp is now in position for use, and the power is applied at the flexible joint or shield 21. When the power 60 begins to draw on the pull rope, it will readily be seen that the slack is taken up in the portions 12 and 13, the pull rope is drawn taut, the two blocks are consequently made to grip the wire or cable 5, and the 65 device is thus securely and rigidly held in position on the wire or cable. The curve or undulating formation of the grooves as described assists in holding the wire or cable and preventing slipping. It will readily be 70 seen that the device may be adjusted to any point or position on the wire or cable by slackening the pull rope, and if desired, the device may be readily opened by lifting or withdrawing the portion 13 of the pull rope 75 from the two hooks 9, 9. When making a pull if it is found that the device is not located in the proper position, the strain on the pull rope is released, and then the clamp may be adjusted by slipping it backward or 80 forward on the wire or cable until the proper position is found. The friction or gripping action of the grooved blocks on the wire or cable is positive, and direct so that 85 there is no likelihood of the device slipping and damaging the wire or cable by tearing or breaking the strands.

From the above description taken in connection with my drawings it is apparent that I have provided a device which is 90 facile in manipulation, is economical and efficient in operation, and which provides a device that is comparatively perfect, and performs its functions in a highly commendable manner.

95 I claim:

A hinged rope clamp, a pair of blocks and a pull rope attached to the end of each, and on each block having eyes at one side of the clamp through which one end of the 100 pull rope is permanently passed, and other cleats on the blocks having alternating eyes and hooks over which the other end of said pull rope may be detachably engaged.

In testimony whereof I affix my signature 105 in presence of two witnesses.

SAMUEL C. SWISHER.
